(57) **CLAIM**

The ornamental design for a barbecue grill shaped like globe, as shown and described.

DESCRIPTION

FIG. 1 is a front top perspective view of a barbecue grill showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right end elevational view thereof; and,

FIG. 7 is a left end elevational view thereof.

The broken lines showing the barbecue cart, including the console panel with controls and the gas tank, are for illustrative purposes only and form no part of the claimed design.
